EDWARD B. HESS AND LEWIS C. MYERS, OF BROOKLYN, NEW YORK, ASSIGNEES TO
ROYAL TYPEWRITER COMPANY, INC., OF NEW YORK, N. Y., A CORPORATION OF
NEW YORK.

TYPE-WRITING MACHINE.

1,208,155.

Specification of Letters Patent. Patented Dec. 12, 1916.

Application filed May 3, 1915. Serial No. 25,384.

To all whom it may concern:

Be it known that we, EDWARD B. HESS and LEWIS C. MYERS, of the borough of Brooklyn, county of Kings, and State of New York; citizens of the United States of America, have jointly invented certain new and useful Improvements in Type-Writing Machines, of which the following is a specification.

10 The improvements in typewriting machines of this invention relate to means for protecting the pivotal connections of the type actuating mechanism and also for affording means for centralizing the rocking 15 ends of the key levers with their bearing supports whereby the bearing rod or shaft may be readily and freely applied in assembling the key levers. It also includes an improved front link support and other features of construction hereafter fully described, reference being had to the accompanying drawings, which illustrate the improvements applied to the Royal typewriter.

Figure 1 is a central section of the machine, looking toward the left: Fig. 2, an enlarged view of the combined dust guard or shed and centralizing means for the rocking ends of the key levers: Fig. 3, illustrates a portion of the bearing rod of the key levers. 30 The parts of a Royal typewriter shown to illustrate the application of the features of this invention thereto may be briefly stated as consisting of the main frame 6, carriage 7, carriage shift 8, platen 9, spacing lever 10, paper pan 11, type bars 12, type head rest 13, universal bar 14, ribbon spool cover or housing 15 and top casing and dust guard 16.

The key levers 17 are each connected by 40 a vertical link 18 to a front link 19 connected at the rear end to type bar 12 by a link 20. To link 20 is secured a bar or link 21 having the rear end bent to engage the universal bar 14. On each universal bar connecting link 21 is a spring 22 whose rear end connects with an adjustable rocking frame 23.

The rounded inner ends 24 of the key levers 17 are carried on the comb bar or bearing bar 25 extending across the machine. Applying the bearing rod or shaft to support and afford a rocking means for the inner or rear ends of the key levers, as these parts now exist, is a troublesome oper-

ation, difficulty often occurring in properly 55 locating the holes in the levers for the passage of the rod. To insure quick and easy performance of this operation, a centralizing or alining plate 26 is secured to the comb bar 25. It extends upwardly and over 60 the ends of the key levers, the vertical and horizontal parts being so arranged as to clear the ends of key levers when they are in operative position, and to provide a guide 65 for alining the holes of the key levers with the holes of the supporting comb 25, as shown at Fig. 2. From this view it will be seen that the bearing shaft or rod 27 may be readily slipped through the holes, the key levers being merely set in the spaces of 70 the comb support, and to facilitate the insertion of the rod 27 its end may be pointed, as at 28. This plate 26 has a dual function. It acts as an alining means for the key levers and also as a dust cover for the working 75 bearings of said levers, the upper horizontal part 29 extending forward over the levers sufficiently to protect the bearings from any dust or dirt that may fall from or between the type bars.

80 The supporting bar 30 carrying the bearings of the front links 19 has a flange 31 at its inner or rear side to protect the bearings from dirt from the inner part of the machine, the links being bent, as shown, to extend down under the flange 31 and beneath the type head rest 13. The upper side of the bar 30 is sloped downwardly toward the front and above it is secured a dust guard or shed 32, whose upper part is laterally curved 85 to conform to the curvilinear arrangement of the type heads, to afford free access for 90 cleaning the type. Its front part 33 extends downwardly to the key board, acting as a protecting apron for the front of the machine.

95 The annexed drawings show certain devices at the rear end of the machine for adjusting the springs which surround the links which connect the universal bar with the type bar links. Such subject matter is not claimed herein but is claimed in our application for Patent No. 91,060, filed April 14, 1916.

We claim:

100 1. In a typewriting machine, key levers, a bearing bar for the rear ends of the key levers, an alining plate extending upwardly

105

in rear of the bearing bar and having its top above the rear ends of the key levers thus serving to align the pivot holes of said levers, and a pivot rod connecting the key levers with the bearing bar.

2. In a typewriting machine, key levers, a bearing bar to which the rear ends of the key levers are pivotally connected and a guard secured to the bearing bar and extending upwardly and over the ends of the key levers to protect their bearings from dust and adapted to guide the ends of levers to align their holes with the bearing holes of the bearing bar and a bearing rod or shaft having a pointed end by which it may be readily inserted through the holes of the levers and holes of the bearing bar.

3. In a typewriting machine, key levers, a bearing bar to which the rear ends of the key levers are pivotally connected, front links of link systems for operating the type bars, vertical links connecting the key levers to the front links, and a supporting bar provided with bearings for the front links and having at its rear side a downwardly extending flange, said front links being formed with a bend to extend under said flange.

4. In a typewriting machine, key levers, a bearing bar to which the rear ends of the key levers are pivotally connected, front links of link systems for operating the type bars, vertical links connecting the key levers to the front links, a supporting bar provided with bearings for the front links and having its upper side inclined downwardly toward the front edge, and a dust guard formed to seat on the upper side of the front link supporting bar and to extend downwardly to the key levers in front of the machine.

5. In a typewriting machine, key levers, a bearing bar to which the rear ends of the key levers are pivotally connected, front links of link systems for operating the type bars, vertical links connecting the key levers to the front links, a supporting bar provided with bearings for the front links and having its upper side inclined downwardly toward the front edge and a dust guard formed to seat on the upper side of the front link supporting bar and to extend downwardly to the key levers in front

of the machine, the upper part of said dust guard being shaped to conform to the curvature of the face line of the type heads.

6. In a typewriting machine, key levers, a bearing bar to which the rear ends of the key levers are pivotally connected, front links of link systems for operating the type bars, vertical links connecting the key levers to the front links, a supporting bar provided with bearings for the front links and having at its rear side a downwardly extending flange and its upper side inclined downwardly toward the front edge and a dust guard secured to said bar and shaped to conform to the curvature of the face line of type heads.

7. In a typewriting machine, key levers, having their rear ends perforated and rounded, a bearing bar to which the rear ends of the key levers are pivotally connected and a guide plate attached to the bearing bar and extending upwardly therefrom in rear of the levers and over the top of their rounded rear ends for controlling the ends of the key levers as the parts are being assembled to set the holes in the levers in alignment with the bearing holes of the bar to facilitate the insertion of a bearing rod or shaft.

8. In a typewriting machine, key levers, a bearing bar to which the rear ends of the key levers are pivotally connected, front links of link systems for operating the type bars, vertical links connecting the key levers to the front links, a supporting bar provided with bearings for the front links and having at its rear side a downwardly extending flange and its upper side inclined downwardly toward the front edge, a dust guard secured to said bar and shaped to conform to the curvature of the face line of type heads, and a guard plate secured to the key lever bearing bar and extending around the ends of the key levers to protect their bearings from dust.

In testimony whereof, we have hereunto subscribed our names.

EDWARD B. HESS.
LEWIS C. MYERS.
